UNITED STATES PATENT OFFICE

ARCHIBALD C. SMITH, OF ROCHESTER, NEW YORK, ASSIGNOR TO UNITED SHOE MANUFACTURING CORPORATION, OF PATERSON, NEW JERSEY, A CORPORATION OF NEW JERSEY

SHOE FINISHING MACHINE

Application filed June 1, 1928. Serial No. 284,853.

This invention relates to shoe finishing machines of the type in which a heated tool is used for performing a burnishing operation on some part of a shoe as, for example, the edges of a sole.

In machines of this type employing a rapidly vibrating iron, it is desired to mount the iron so as to permit a limited angular movement for purposes of self-adjustment in the iron. It will be apparent that such an arrangement subjects the iron to severe wearing conditions and, in commercial practice, many irons have to be discarded before their operating faces are worn out on account 10 of the excessive angular play which develops in the holder on account of this wear.

In one of its aspects, the present invention consists in a novel construction of holder and iron whereby the necessary limited angular play is permitted and at the same time excessive and objectionable wear is eliminated. To this end, and in accordance with an important feature of the invention, the illustrated iron and holder have a swivel connection which includes a socket with a complete unbroken cylindrical surface and a positioning member having a flat face of substantial area acting on the exterior of the iron to resist the rotation of the tool and to limit its angular movement in the holder. By thus providing contact faces of substantial area, the wear upon the iron is eliminated or reduced to a minimum. In machines of this type, it is a practice to employ interchangeable tools or irons shaped in accordance with the contour of the particular work to be operated upon and it is important, accordingly, so to design the tools that they may be readily removed from the holder and 30 as readily replaced in operative position.

The pressure of the latch ordinarily employed to retain the edge iron on the holder is insufficient appreciably to hinder the removal of the iron or the replacement of another. However, if, in addition to a latch for retaining the iron on the holder, a positioning member for resisting rotation of the iron on the holder is arranged to bear squarely against the iron, the increased frictional 40 resistance between the iron and its holder,

owing to the pressure of the positioning member against the iron, may be sufficient to cause difficulty in the removal of the iron from the holder. It is therefore another object of the invention to provide, in a burnishing machine having a latch for holding the edge iron to the holder, means for limiting the angular movement of the edge iron necessary for its self-adjustment, the presence of which means does not render the 55 removal of the iron from the holder any more difficult. In accordance with this feature of the invention the flat face on the iron is disposed obliquely to its axis so that, upon a very slight retractive movement of the iron, the obliquely disposed face is removed 60 from engagement with the cooperating positioning member. In order that there shall be no lost motion between the edge iron and the positioning member, when such a condition is desired, the latch is constructed and arranged to engage a face on the iron oppositely inclined to the face of the iron which is engaged by the positioning member; and the latch, therefore, acting against the 70 cooperating face on the edge iron, tends to move it to hold the iron in engagement with the positioning member. Similarly, the positioning member, bearing against the inclined coöperating face on the edge iron, resists any rotative movement thereof and provides an abutment for the iron determining 75 its position on the holder.

In one form of shoe finishing machine, the tool is heated by a stationary heating unit 80 having a plane radiating face, the tool being located and moved in close proximity thereto. Another feature of the invention consists in a novel form of iron adapted particularly well to cooperate with a heating unit of this character and, accordingly, to improve the efficiency of the heat transfer. To this end, the illustrated iron is formed with the side 85 which is disposed toward the heating unit as a continuous flat face extending from one end of the tool to the other and for the full width thereof. In this way, the maximum area of the tool is made available to receive heat by radiation.

In machines wherein the burnishing iron 100

is oscillated at a high rate of speed, it has been found that a smoother action and less vibration of the machine is secured by making the general contour and construction of the iron symmetrical. In another aspect, accordingly, the present invention provides a burnishing iron having a symmetrically located bore, the bore of the illustrated iron having a complete unbroken surface and being provided with a retaining groove and a positioning face so designed as to maintain the symmetry and balance of the parts to the greatest degree possible. An iron of such construction may be used advantageously in shoe finishing machines of different types and the invention in this respect is, therefore, of general application.

These and other features of the invention will be best understood and appreciated from the following description of a preferred embodiment thereof, selected for purposes of illustration and shown in the accompanying drawings, in which

Fig. 1 is a view in side elevation, partly in section, of the head of an edge setting machine;

Fig. 2 is a view in perspective, on an enlarged scale, of the tool, the tool holder and the electric heating unit; and

Fig. 3 is a view in perspective of the holder and tool separated from each other.

Since the invention may be applied to edge setting machines of any commercial type, it is not deemed necessary to illustrate the whole machine herein and, consequently, only the head is shown. This comprises an oscillating rock shaft 10 which projects outwardly from a frame 12 and which is oscillated at a high rate of speed in a fashion common in such machines. Upon the outer end of the shaft is mounted a head 14 having oppositely projecting arms 15 and 17 which are recessed to receive cylindrical tool holders 16. The tool holders 16 are yieldingly mounted in the receptacles in the head and retained in place by stop bars 20 set in the head 14 and traversing a slot formed in the body of the holder, as shown in Fig. 2. Each of the holders 16 carries a detachably mounted edge iron and it is customary to equip the machine with a forepart iron in one holder and a shank iron in the other. The head 14 is latched in operative position but is arranged to be rotated through half a revolution to present either iron in operative position, as required by the operator.

The mechanism for holding and rotating the head will not be herein described since it forms no part of the present invention. The head illustrated, however, is similar to that shown in Letters Patent of the United States No. 1,757,188, granted May 6, 1930, on an application of William Hamann, to which reference may be had for a complete disclosure of this construction. Electrical heating

units 30, each having a flat radiating face, are mounted in the machine in stationary position so as to heat both irons, that is to say, the lowermost iron while it is in operative position and the uppermost iron while it is in inoperative position.

Each tool holder 16 comprises a plunger having a projecting swivel pin 22 at its outer end. Each plunger has a flat portion formed adjacent to its end, to which are adjustably secured a spring retaining leaf or latch piece 24 and a positioning member 26. Both of these members are of sheet material and each has a slotted shank for the reception of a clamping screw 25. The retaining member 24 is curved inwardly at its outer end to constitute a spring detent. The outer end of the positioning member 26 is bent inwardly at an acute angle, forming a portion 28 with a face disposed obliquely with respect to the spindle 22 and having a substantial area. The members 24 and 26 are assembled in superposed relation and may be adjusted longitudinally together or separately and clamped in adjusted position by the screw 25.

The burnishing tool or iron 40 is formed with its end surface to fit the edge contour required in the sole being operated upon. The body of the iron is substantially rectilinear in shape and provided with a longitudinal bore 42 disposed symmetrically so that the iron will be in substantial balance about its longitudinal axis. It will be seen that the bore 42 has a continuous unbroken cylindrical wall, there being no key or keyway in either the pin 22 or its corresponding socket. In this way, a maximum bearing surface is provided between the iron and the pin upon which it is mounted and the best possible conditions of wear are thus secured.

In its outer face, the iron 40 is provided with a transverse groove 44 of curved contour which cooperates with the curved end of the spring retaining member 24 when the iron is positioned upon the pin 22 to detachably retain the iron against longitudinal displacement. At the same time, the iron may be removed when desired by forcing it sufficiently to spring the end of the retaining member out of the groove. Between the groove 44 and the inner end of the iron is formed a positioning face 46 which is disposed obliquely at an acute angle to the axis of the iron and oppositely inclined to the adjacent side of the groove 44. This face cooperates with the transverse positioning face 28 of the member 26 when the iron is held in operative position by the spring detent as shown for example, in Fig. 2. The contact face 46 of the iron and the corresponding face of the inturned end 28 of the positioning piece bear over a substantial area and serve to limit the angular movement of the iron upon the pin 22. This movement, as already stated, must be slight but should preferably be provided for. The

member 26 being backed up by the retaining member 24 may spring slightly in permitting this limited angular movement or if desired it may be adjusted so as to separate the contact faces slightly and permit the necessary movement to occur as lost motion between the two faces.

It will be understood that the inner or rear face of the iron which is disposed toward the heating unit 30 is formed as a continuous flat face extending from one end of the tool to the other and for the full width thereof. This face is located in close proximity to the plane radiating face of the heating unit and, accordingly, the iron presents the most favorable shape possible for receiving heat by radiation from the heating unit.

Having thus described my invention, what I claim as new and desire to secure by Letters Patent is:

1. A burnishing head including a holder having a projecting pin, a burnishing iron having a socket with an unbroken cylindrical wall to receive said pin, means connected to the holder and acting upon the exterior of the iron to prevent it from twisting on the pin, and means for retaining the iron against longitudinal displacement on the pin and for holding the iron against said anti-twisting means.

2. A burnishing head including a holder having a projecting pin, a spring member with a laterally extended face, and a latch piece, in combination with a burnishing iron having a complete unbroken socket surrounding said pin, a laterally extending face on the iron disposed in contact with the face of the spring member, and a shoulder on the iron cooperating with the latch piece to hold the laterally extending faces of the spring member and the iron in engagement to resist twisting of the iron.

3. A burnishing head including an elongated holder with a positioning member projecting therefrom and having its outer end shaped to afford a flat face of substantial area disposed obliquely toward the axis of the holder, a burnishing tool having an oblique face arranged to engage the face of the positioning member, and means constructed and arranged to hold said tool and said positioning member in engagement whereby twisting of the tool is resisted.

4. A burnishing head including a holder having a pin and a positioning member secured thereto, said positioning member projecting from the holder adjacent to the pin and having its end bent to afford a flat face of substantial area disposed obliquely toward the pin, a burnishing tool mounted on said pin and having an oblique face cooperating with the face of the positioning member to resist twisting of the tool, and means cooperating with said positioning member to oppose any axial displacement of said tool on the pin.

5. A burnishing head including a holder having a pin, a positioning member adjustably secured to the holder and having its end bent back at an acute angle to form an offset positioning face, and a burnishing tool mounted on said pin and angularly positioned by said face.

6. In a shoe finishing machine, an oscillating head having a holder, a heating unit with a plane radiating face, and a burnishing iron projecting from said holder and having a flat face movable in a plane parallel with and adjacent to said radiating face.

7. In a shoe finishing machine, an oscillating head having a holder, a heating unit with a plane radiating face, and a burnishing tool projecting from said holder and having its side which is disposed toward said heating unit formed as a continuous flat face extending from one end to the other of the tool and for the full width thereof.

8. In a shoe finishing machine, an oscillating head having a holder comprising a projecting pin, a burnishing tool slidably mounted on said pin having oppositely inclined flat faces, and means engaging each of said faces and tending to move the tool toward the other of said means, thereby resisting the rotation of said tool on the pin.

9. A burnishing head including a holder having a pin and a positioning member secured thereto, said positioning member projecting from the holder and having its end bent to afford a flat face, a burnishing tool mounted on said pin having a face constructed and arranged to engage the face of the positioning member thereby to resist any twisting of the tool, and means cooperating with said positioning member to oppose any axial displacement of said tool on the pin.

In testimony whereof I have signed my name to this specification.

ARCHIBALD C. SMITH.
